UNITED STATES PATENT OFFICE

JOHN WILEY, OF LANCASTER, PENNSYLVANIA, ASSIGNOR TO ARMSTRONG CORK COMPANY, OF LANCASTER, PENNSYLVANIA, A CORPORATION OF PENNSYLVANIA

MANUFACTURE OF INLAID LINOLEUM OR THE LIKE

Application filed May 24, 1929. Serial No. 365,625.

This invention relates to the manufacture of inlaid linoleum or the like and is particularly directed toward an improved method and machine for the production of so-called straight-line linoleum.

A large amount of straight-line linoleum is manufactured on the well-known rotary machine. Machines of this type are very large and expensive but are effective for producing large quantities of material at high speed. However, the range of patterns which can be produced thereby is relatively limited. By my invention the number of patterns which can be manufactured is materially enlarged and highly desirable effects are obtainable.

The rotary machine now in use employs die rolls having a circumference of 54 inches. The pattern repeats three times around this die roll as it is necessary to employ pin rolls for ejecting the scrap material and for applying the remainder to the backing, and these pin rolls must lie within and move in synchronism with the die rolls. The pattern is repeated three times around the die rolls in present machines in order that the small pin rolls may actuate the strippers employed.

I have found that it is only necessary to actuate a stripper under a portion of a piece of linoleum on the surface of a die roll, and that if proper precautions are taken, a piece materially larger than the stripper may be ejected. I am therefore able to actuate strippers spaced around a die roll with a single actuating pin on the pin roll, but to vary the pattern by having these strippers eject portions of different size or shape. There is thus obtainable a pattern having a repeat length up to the circumference of the die roll, and where pattern elements having such repeat length are applied to the backing, together with other pattern elements (applied by other die rolls) having the normal repeat

length, a wide variety of effects may be obtained.

My invention is particularly valuable in connection with the invention of Charles F. Humphreys, described and claimed in his application, Serial No. 363,581, filed May 16, 1929. In that application there is described a method of making linoleum or the like by applying pattern elements by the die rolls to a portion only of the backing, other portions of the backing being covered by pattern elements which are applied by hand. This is particularly desirable for the application of haphazard spots of color which contrast with the general background of the design, and by my invention spaces in which the haphazard spots are applied may be left as much as 54 inches apart.

In the accompanying drawings illustrating the present preferred embodiment of my invention as applied to the production of a tile pattern,

Figure 1 is a diagrammatic view of the rotary machine;

Figure 2 is a transverse view through one of the die rolls employed;

Figure 3 is a view taken on the line III—III of Figure 2;

Figure 4 is a view corresponding to a portion of Figure 2 and illustrating a modified construction; and

Figure 5 is a progressive view showing the steps in the manufacture of the tile pattern, the view being divided into parts 5a and 5b for convenience of illustration.

The machine illustrated in Figure 1 comprises a drum 2 having die rolls 3 spaced therearound. Each die roll is supplied with webs 4 of linoleum mix from calenders 5 having doctor blades 5a. The calendered material is carried to the die rolls on belts 6. Platen rolls 7 cooperate with each die roll. As is well known, each die roll has cutting knives on its surface, these knives being arranged to cut into the web of linoleum mix 90

and divide it into pattern elements and scrap. Pin rolls 8 lie within the die rolls 3 and rotate therewith, the pins being effective for actuating strippers, hereinafter described, which discharge the scrap material into conveyor troughs 9. Upon continued rotation of the die rolls, those portions which are not discharged as scrap are applied to a web 10 of backing material. There is a separate die roll for each color employed in the general body of the pattern, and after the several colors have been applied by the machine the material travels over an inspection table 11 to a calender indicated generally by the reference character 12. After being calendered, the material is carried to the stove for curing.

One of the die rolls 3 is shown in detail in Figure 2. It comprises a shell 13 having Babbitt blocks 14 over the surface thereof, these blocks engaging knives 15 placed therebetween. Each knife-bounded area is provided with a stripper 16 having a pin 17 projecting inwardly of the shell 13 so as to be engaged by the pins of the pin roll 8. The pin roll 8 is commonly known as the scrap roll and its function is to eject those portions of the linoleum web which are not to be applied to the backing 10. A second pin roll—the so-called pattern roll—is shown at 18. The function of this roll is to actuate those strippers which were not actuated by the scrap roll 8 so as to force the remaining pieces of linoleum mix outwardly against the backing 10 as it moves with the drum 2 past the die rolls.

It is difficult, if not impossible, to so place the knives 15 on the periphery of the die roll that they will all be of exactly the same height. The cutting edges will usually vary in height by a few thousandths of an inch and it is therefore customary to provide a clearance of about five thousandths of an inch between the die roll and the platen 7 so that the linoleum mix is not cut entirely through. The cutting is completed by a stiff brush 7a which engages the face of the material and pushes it down into the spaces between the knives. After the cutting has thus been completed, the strippers are actuated so as to discharge the scrap. The discharge of the scrap is facilitated by a brush 19 which engages the edges of the linoleum pieces as they are pushed outwardly by the strippers. I have found that with this arrangement, discharge of scrap can be effected even though the piece is materially larger than the stripper.

I have illustrated in Figure 3 a stripper 16a whose head has a length L, measuring longitudinally of the die roll. The head of the stripper 16a lies within a knife bounded area of length L'. The stripper 16a is arranged to be actuated by a pin 8a on the scrap roll 8 and this same pin 8a also actuates strippers 16a' and 16a''. The knife bound-

ed areas for the strippers 16a' and 16a'' are of length L, there being a knife inserted between the blocks 14 in slots corresponding to the slot 20 in Figure 3. In the case of the strippers 16a, however, such knife is omitted, 70 as shown in Figure 3.

When the strippers 16a' and 16a'' are actuated they eject pieces of linoleum of length L, whereas the stripper 16a ejects a piece of linoleum of length L', the piece being 75 forced out from between the rolls by the stripper as indicated at 21, and the edge thereof being engaged by the brush 19.

Adjacent each of the strippers 16a' and 16a'' is another stripper occupying the position corresponding to that shown at 16b in Figure 3. It is not essential that a stripper 16b be provided adjacent the stripper 16a since if one is present it is not active. However, the corresponding strippers adjacent the strippers 16a' and 16a'' are actuated by pins in the pattern roll 18 and are effective for laying squares of linoleum on the backing 10. If a stripper 16b is provided alongside of the stripper 16a, it will be actuated by the same pin in the pattern roll as actuates the corresponding strippers alongside the strippers 16a' and 16a'', but since a piece of linoleum of the length L' has been ejected by the stripper 16a, it cannot lay any 95 material on the backing 10.

From the foregoing it will be seen that at one rotation of the die roll there will be laid on the backing 10 a square of linoleum by the stripper alongside the stripper 16a' and a similar square will be laid on the backing by the stripper alongside the stripper 16a'', these two squares being 18" apart on the goods. However, the stripper 16b will not lay any material and there will therefore be a gap of 36" before there is again laid a block of linoleum on the backing by any of the strippers alongside the strippers 16a, 16a' and 16a''. It will be understood, of course, that other pins and strippers will cover other parts of the backing. However, so far as this particular set of strippers is concerned, a repeat length other than 18 inches is obtained.

Referring now to Figure 5, there are shown the successive steps in the production of a linoleum tile pattern. In the portion D1 there are applied to the backing 10 pattern elements PI of linoleum by the lowermost die roll 3. In this particular case my special die roll is the second one which engages the product and the effect thereof is shown in the portion D2 of Figure 5. I have shown spaced squares X which correspond to the areas over which the strippers 16a, 16a' and 16a'' pass. I have shown at S the area corresponding to that over which the stripper 16b passes. By reason of the fact that the stripper 16a was effective for ejecting as scrap a piece of material of width L' (corresponding to the width of the area X plus the width of the area S) the 130

area S receives no pattern element. However, the areas S' and S'', lying alongside those areas X which correspond to the stripers 16a' and 16a'', are supplied with pattern elements by the die roll.

The portions D1 and D2 are each illustrated as being 54 inches long—the circumference of each die roll—these lengths being subdivided into three portions of length d_1 and d_2 , each 18 inches long. It will be noted from the portion D1 that the pattern elements applied by the first die roll repeat in each distance d_1 ; that is to say, they have the normal repeat length of 18 inches. This is also true in the portion D2, except that D2 differs from the other sections in the omission of the square S. Therefore, while the second die roll applies a pattern which in most particulars repeats itself every 18 inches, such pattern, considered as a whole, repeats itself only every 54 inches. With the exception of the area S, the uncovered portions of the backing are the same in each of the portions d_2 .

The third die roll is effective for filling in the remainder of the general body of the pattern. The pattern applied by the third die roll is shown at D3 and it will be seen that in this particular case none of the backing except at the square S is left exposed. It will be understood, of course, that my invention may be applied in those cases where the pattern elements are spaced apart so as to produce embossed effects.

After the material leaves the third die roll no more pattern elements are applied by the machine and the portion D3 of Figure 5 represents the appearance of the goods as they travel over the inspection table 11. During this travel a brightly colored block is filled in by hand in the area S indicated at 22. These color blocks are spaced 54 inches apart and different colors may be used so as to give still further variety to the pattern.

I have illustrated in Figure 4 a modification wherein a stripper 23, having a width W as measured around the circumference of the die roll, is effective for stripping a section of width W' as measured around the die roll, there being a knife omitted at 24 so that the stripper 23 engages a piece of linoleum materially larger than the stripper head. Where this arrangement is used the squares corresponding to the squares X of Figure 5 will lie in the same line as the squares corresponding to the squares S thereof, instead of sidewise thereof.

I have illustrated and described the present preferred embodiment of my invention and a modification thereof. It will be understood, however, that it is not limited to the form shown but may be otherwise embodied and practiced within the scope of the following claims.

I claim:

1. In a machine for the manufacture of

linoleum or the like, a die roll having knives adapted to cut and define an area of material to be discharged as scrap, stripper means carried by the die roll and lying within a knife-bound area thereof, such stripper means being operable to raise a portion only of the material within the knife-bound area, and means for engaging the lifted portion.

2. In a machine for the manufacture of linoleum or the like, a die roll having knives adapted to cut and define an area of material to be discharged as scrap, stripper means carried by the die roll and lying within a knife-bound area thereof, such stripper means being operable to raise a portion only of the material within the knife-bound area, and a brush for engaging the lifted portion.

3. In a machine for the manufacture of linoleum or the like, a die roll having stripers spaced therearound and arranged in sets, and a common actuating means for a group of strippers made up of a stripper in one set and the corresponding strippers in the other set, different strippers in the group being adapted to discharge scrap portions of different size or shape.

4. In a machine for the manufacture of linoleum or the like, a die roll having knives arranged therein adapted to cut material into portions, the knives being arranged in a general pattern which repeats around the die roll, but there being a knife-bounded area in one repeat differing from the corresponding area in another repeat, strippers for ejecting the material in such areas, and a common means for actuating the strippers.

5. In a machine for the manufacture of linoleum or the like, a die roll having knives arranged therein adapted to cut material into portions, the knives being arranged in a general pattern which repeats around the die roll, but there being a knife-bounded area in one repeat differing from the corresponding area in another repeat, strippers for ejecting the material in such areas, a common means for actuating the strippers, and means effective for engaging the edges of the several portions of material ejected by such strippers.

6. In the method of making inlaid linoleum or the like, in a machine having die rolls, the steps consisting in applying to a backing, by one die roll, pattern elements arranged to repeat at a desired interval, and applying, by another die roll, other pattern elements arranged to repeat at another interval.

7. In a machine for the manufacture of linoleum or the like, a plurality of die rolls adapted to apply pattern elements to a backing, one die roll being effective for applying pattern elements in a series arranged to repeat at a desired interval, and another die roll being adapted to apply pattern elements

in a series arranged to repeat at another interval.

8. In the method of making inlaid linoleum or the like in a machine having die rolls, the steps consisting in applying to a backing, by one die roll, pattern elements arranged to repeat at a desired interval, applying, by another die roll, other pattern elements arranged to repeat at another interval, and adding other pattern elements by hand.

9. In the method of making inlaid linoleum or the like in a machine having die rolls, the steps consisting in applying pattern elements by a die roll, the pattern elements being spaced apart but arranged to repeat at desired intervals, and applying other pattern elements by another die roll or die rolls to fill all the gaps between pattern elements in certain repeat lengths and to fill less than all of the gaps in other repeat lengths.

10. In the method of making inlaid linoleum or the like in a machine having die rolls, the steps consisting in applying pattern elements by a die roll, the pattern elements being spaced apart but arranged to repeat at desired intervals, applying other pattern elements by another die roll or die rolls to fill all the gaps between pattern elements in certain repeat lengths and to fill less than all of the gaps in other repeat lengths, and completing the filling in of the pattern by hand.

11. In a machine for the manufacture of linoleum or the like, a die roll adapted to apply pattern elements which are spaced apart but which repeat at a desired interval, and another die roll or die rolls arranged to apply other pattern elements between the first mentioned pattern elements so as to fill all the gaps therebetween in certain repeat lengths and to fill less than all the gaps in other repeat lengths.

12. In a machine for the manufacture of linoleum or the like, a die roll having knives on the periphery thereof, a platen spaced from the die roll so that material passing between the die roll and the platen will be partially but not entirely cut through by the knives, stripper means carried by the die roll and lying within a knife-bounded area thereof, such stripper means being operable to raise a portion only of the material within the knife-bound area, and means adapted to engage material within the knife-bounded area when raised from the die roll by the stripper.

13. In a machine for the manufacture of linoleum or the like, a die roll having knives on the periphery thereof, a platen spaced from the die roll so that material passing between the die roll and the platen will be partially but not entirely cut through by the knives, stripper means carried by the die roll and lying within a knife-bounded area thereof, such stripper means being operable to

raise a portion only of the material within the knife-bound area, and a brush adapted to engage material within the knife-bounded area when raised from the die roll by the stripper.

14. In a machine for the manufacture of linoleum or the like, a die roll having knives adapted to cut and define an area of material to be discharged as scrap, and a stripper lying within the area defined by the knives, the stripper having a conformation differing materially from the conformation of the area defined by the knives.

In testimony whereof I have hereunto set my hand.

JOHN WILEY.
